Specification of Letters Patent.

Patented Nov. 1, 1921.

Application filed September 11, 1920. Serial No. 409,550.

To all whom it may concern:

Be it known that I, ARCHIBALD JACKSON STRANE, a citizen of the United States of America, residing at Tamaqua, in the county 5 of Schuylkill and State of Pennsylvania, have invented certain new and useful Improvements in Presses, of which the following is a specification.

This invention relates to presses and more 10 particularly to presses designed to simultaneously press a multiplicity of objects. The primary object of the invention is to provide a press of this character whereby each of the press points of the press may be caused to 15 exert an individually controllable degree of pressure upon the object which it engages to the end that a uniform degree of pressure may be exerted upon the objects being pressed irrespective of variations in the degree 20 of thickness of the objects pressed or in the degree of preparation for pressing of said objects or to the further end that different degrees of pressure may be exerted upon the objects being pressed, if this be 25 desired.

It is a further object of the invention to provide a press of the character above set forth wherein the movable press head may be given a quick movement to approximate 30 pressing position and thereafter given a relatively slower but correspondingly more powerful movement to complete the pressing operation.

Further objects and advantages of the invention will be set forth in the detailed description which follows.

In the accompanying drawing:—

Figure 1 is a view partly in side elevation and partly in section of a press constructed 40 in accordance with the invention, and

Fig. 2 is a fragmentary plan view thereof.

Like numerals designate corresponding parts in both of the figures of the drawing.

Referring to the drawing 5 designates a 45 movable press head the shank 6 of which travels in a guide 7 carried by the bed 8. A guide block 9 and guide plate 10 mounted upon supports 11 and 12 have press points 13 mounted to move vertically therein. The 50 guide block 9 is stepped as indicated at 14 and the press points are provided with heads 15 which rest upon the upper faces of these steps. By referring to Fig. 2 it will be seen that these press points are arranged in rows

along the several steps. A work plate 17 55 carried by the head 5 receives the objects A that are to be pressed, these objects being alined with the lower ends of the press points.

Levers 18 are fulcrumed at 19 and their 60 free ends rest upon the heads 15 of the press points. Weights 20, only one of which is shown, are connected by cables 21 with the ends 22 of the levers 18. These cables are passed over pulleys 23 in such manner that 65 the weights act to move the free ends of the levers downwardly and thereby cause said levers to exert a pressure upon the press points proportional to the size or weight of the weight 20. Thus it will be apparent that 70 when, during upward movement of the press head 5, a predetermined degree of pressure has been given the objects A no further pressure will be exerted upon these objects even though said head continues its upward movement because after that degree of pressure has been reached the press points will yield 75 upwardly. Thus a uniform degree of pressure may be exerted upon each and every one of the objects A if all of the weights are the 80 same or any individual press point or row of press points may be caused to exert a pressure different from the others by properly varying the weights. It is manifest that springs may be substituted for the weights 85 and the same result be secured.

Any desired means for actuating the head 5 may be employed. This head may be actuated by hand or it may be actuated by power or a combination of the two may be 90 used. For purposes of illustration I have shown a hand operated toggle combined with a hydraulic plunger the arrangement being designed to give a quick lift to the head 5 under the influence of the toggle, to the 95 point where the objects A are just engaged with the press points, the actual pressing operation being accomplished by power through the medium of the hydraulic plunger. The construction referred to comprises the toggle links 24 and 25, link 26, bell crank lever comprising the arms 27 and 28, the latter forming a handle and a hydraulic plunger 29 operable in a hydraulic cylinder which is conventionally indicated 100 at 30.

It is to be understood that the invention is not limited to the construction shown because

said construction is intended to be merely explanatory of the principles involved. Many modifications of the arrangement and refinements thereof will readily suggest themselves to the engineer skilled in the art. It is therefore to be understood that the invention includes within its purview whatever changes fairly come within either the terms or the spirit of the appended claims.

10 Having described my invention, what I claim is:

1. In a multiple press a plurality of press points, a work-carrying head movable toward said press points to simultaneously bring the work into engagement with all of said press points and individually adjustable weighted pressure creating means for each of said press points.

2. In a multiple press a plurality of press points, a work-carrying head movable toward said press points to simultaneously bring the work into engagement with all of said press points, a pivoted lever for each of said press points and means engaged with said levers and acting through said levers to exert pressure upon the several press points.

3. In a multiple press a work-carrying head mounted for movement, a plurality of press points, a member in which said press points move said member having a stepped upper surface and said press points being supported upon the several steps of said sur-

face, a plurality of levers disposed at varying levels and pivoted uniformly intermediate their ends the inner ends of said levers resting upon the press points and yieldable pressure creating means connected to said levers outwardly of their fulcrums.

4. A structure as recited in claim 3 wherein said press points are disposed in rows along each of said steps.

5. A press comprising a movable work-carrying head in combination with manually operable means for moving said head to approximate pressing position and power means for completing the pressing movement of the head.

6. A press comprising a movable work-carrying head, a hydraulic plunger and a manually operable toggle between the plunger and the head.

7. A structure as recited in claim 6 in combination with a plurality of press points opposed to said head and individually and independently yieldable members engaging said press points and exerting pressure thereon.

In testimony whereof I affix my signature in the presence of two witnesses.

ARCHIBALD JACKSON STRANE.

Witnesses:

CHARLES H. MACINTOSH,
BENNETT GROTTA.
